C. B. DYER

PIN, EMBLEM, MEDAL, RING, OR ARTICLE OF A SIMILAR NATURE

Filed Oct. 21, 1921

INVENTOR.

CHARLES B. DYER.

BY

Al. Bradford

ATTORNEY.

UNITED STATES PATENT OFFICE.

CHARLES B. DYER, OF INDIANAPOLIS, INDIANA.

DESIGN FOR A PIN, EMBLEM, MEDAL, RING, OR ARTICLE OF A SIMILAR NATURE.

Application filed October 21, 1921. Serial No. 509,431. Term of patent 7 years.

To all whom it may concern:

Be it known that I, CHARLES B. DYER, a citizen of the United States, residing at Indianapolis, in the county of Marion and State of Indiana, have invented a certain new, original, and ornamental Design for a Pin, Emblem, Medal, Ring, or Article of a Similar Nature, of which the following is a specification.

The design here shown may obviously be used for medals, rings, emblems, or similar articles.

I claim:

The ornamental design for a pin, emblem, medal, ring or article of a similar nature, as shown.

In witness whereof, I have hereunto set my hand and seal at Indianapolis, Indiana, this 19th day of October, A. D. nineteen hundred and twenty-one.

CHARLES B. DYER. [L. s.]

Witnesses:

M. L. SHULER,
CAREY S. FRYE.
